AUTOGRAPHIC REGISTER

Leslie A. Holman, Waltham, Mass.

Application August 10, 1932, Serial No. 628,145

22 Claims. (Cl. 282—18)

This invention relates to that type of manifolding device commonly known as an autographic register and more particularly to that type of register in which a plurality of sheets or webs are fed over a support or writing table with means interposed between the sheets for transferring any record made on the top sheet to the lower sheets.

In the autographic register in use today, superposed continuous sheets or strips of paper, usually two or more, are fed by suitable mechanical means from a roll or rolls, or a pad or pads, contained in a compartment of the register, over a writing tablet, where sheets of carbon paper are inserted transversely between the superposed strips so as to secure a plurality of copies of the matter written on the top sheet. Generally, upon each of these strips of paper is printed a series of forms of account, consecutively numbered, whereon a record of sales may be recorded, the idea being that the form upon one of the superposed strips of paper is for delivery to the customer and the corresponding numbered form upon another strip is intended as an office record of the transaction, and if there is a third form, that is automatically fed into a locked chamber in front of the machine to be available later for audit or reference purposes. If further copies are required, more than three strips of paper may be used in the manifolding machine. By a revolution of a crank in the manifolding device, or some such similar means, the forms after a transaction has been recorded on the top sheet are advanced in the machine to bring new forms over the writing table and the used forms, with the exception of the audit strip, are torn off and the audit strip is fed intact through the machine, as already mentioned, into a compartment specially provided therefor. It is necessary that the strips of paper in the manifolding machine be in perfect alignment, that is to say, the forms upon the underlying strips of paper bearing the same number as the top form, must be in alignment or registration, the one to the other, so that any inscription made on the upper form upon the writing tablet will be transferred with exactness in all respects to the same numbered underlying forms.

In the manufacture of autographic registers, great difficulty has heretofore been experienced in producing a register adapted for feeding a plurality of webs or strips of paper intermittently in accurate steps and to maintain the webs or strips in perfect register with each other without requiring frequent adjustment of the paper in the

register. No register has heretofore been produced which has been satisfactory in operation in these respects and the registers now in use are open to the objection that frequent adjustments are required which involve loss of time and detract from the efficiency of the register. In many cases, users of a plurality of registers keep an extra substitute machine on hand for use in such emergencies. 5

Another source of difficulty has been that none of the registers in use have insured the delivery of the auditor's copy into the locked compartment in such manner as to eliminate the stopping of the machine due to crumpled paper in that compartment. It frequently happens that the auditor's copy fed into the compartment becomes disarranged or fails to fold as it should, whereupon it begins to crumple with the result that the compartment is soon filled with a crumpled mass of paper and the register is rendered non-usable until the locked compartment has been opened by the proper person, the crumpled record taken out and the paper web readjusted for proper feeding into the compartment. Delays due to this cause are not infrequent and are vexatious involving time and expense and interfering with the orderly conduct of the business in which the register is used. 10 15 20 25

The principal object of the present invention is the elimination of the foregoing difficulties by the production of a register of the type described which is simple and compact in construction, durable and efficient in operation and which will not get out of adjustment or break down in use. 30

One of the important objects of the invention is the provision of means for feeding a plurality of sheets or webs which is positive in its action and which is capable of adjustment to feed said webs an exact predetermined distance on each feeding movement irrespective of any lost motion in the feed operating mechanism and which is designed to maintain accurate register at all times between the webs. 35 40 45

Another object of the invention is the provision of means for severing the used portions of the sheets or webs at the end of each feeding movement. 45

A further object of the invention is the provision of means for feeding one of the severed copies into a locked auditor's compartment and for delivering the other severed copies to the operator of the register. 50

Yet another object of the invention is the provision of a register adapted to be operated either 55

by hand as by a crank or by power such as an electric motor.

Various other objects of the invention will be more specifically set forth and described herein-
5 after.

My invention contemplates an autographic register in which a plurality of strips or webs of paper are drawn over a writing table from a supply in suitable form in the register, the strips or webs of paper at the table being interleaved with transverse strips of transferring material such as carbon coated paper so that a number of copies equivalent to the number of strips or webs is made at one writing. The invention further contemplates the provision of means for feeding the paper forwardly after each writing operation to move fresh portions onto the table, means for severing at the end of each feeding movement, the used portions from the strips or webs and means for delivering the bottom copy into a compartment which may be locked and the other copies to the operator of the register.

One of the important features of my invention consists in providing feeding means adapted to maintain an absolutely exact feed which is not varied or otherwise affected either by the paper gripping and releasing operations or by lost motion of the parts or other causes. This end is accomplished by providing a gripping mechanism and means for imparting a reciprocal movement thereto to feed the paper, said means being so connected to the gripping mechanism that it is operated either to grip or release the paper after it has reached the end of its stroke in one direction or the other. The preferred form of gripping mechanism comprises a pair of jaws and a cam member for opening and closing the same, all mounted on a suitable support for reciprocal movement. For operating the gripping mechanism, a rack-bar or other suitable member, adapted to be reciprocated by suitable means, is connected to the cam member only, said rack-bar being adapted by continued movement, when the gripping mechanism has reached the end of its stroke, to move the cam member to operate the jaws. The force required to operate the cam member is greater than the force required to reciprocate the gripping mechanism so that the jaws are not operated until after the gripping mechanism has stopped. Since the length of the path of this mechanism can be adjusted definitely by the use of suitable stops, the feed of the paper is always exact and perfect alignment and registration is always maintained.

Another feature of my invention resides in providing means for severing the used portions of the paper webs at the end of each feeding movement so that the copies are delivered in separated condition. This feature has marked ad-
60 vantages over the old method of feeding the bottom web in a continuous condition into the locked compartment and tearing off the used portions of the other webs. It eliminates all crumpling and stoppage of the machine which so frequently happens when the bottom web is fed into the compartment in a continuous form and fails to fold properly and it prevents any disturbance of the registration of the webs which sometimes happens when the operator tears the used portions off at the perforations. This feature also tends to save time in the use of the machine because it eliminates the tearing operation at the end of the feeding movement.

For the purpose of illustrating my invention,
75 there is shown in the accompanying drawings

an autographic register constructed and adapted to be operated in accordance therewith, in which, Figure 1 is a plan view of a register provided with a motor for operation by electric power, said register being shown on a reduced scale; Fig. 2 is a plan view of the register with the covers removed to expose the interior mechanisms, the web of paper being shown at the end of a feeding movement with the used portion severed; Fig. 3 is a side elevation of the register with cer-
5 tain portions broken away to expose the interior mechanism; Fig. 4 is a vertical, longitudinal, sec-
10 tional view on line 4-4 in Figure 2; Fig. 5 is a transverse, vertical, sectional view on line 5-5 in Fig. 4, but on a much enlarged scale to show 15 fully the gripping mechanisms in end elevation; Fig. 6 is a side elevation of one of the gripping mechanisms showing the jaws closed; Fig. 7 is a similar view with the jaws in open position; Fig. 8 is a transverse, vertical, sectional view on line 20 8-8 in Fig. 4, showing particularly the severing mechanism; Fig. 9 is a longitudinal sectional view of the severing mechanism showing the position of the parts at the end of the cutting stroke; Fig. 10 is a similar view showing the 25 severing mechanism in normal inoperative position; Fig. 11 is a plan view of the means for guid-
30 ing the bottom copy into the locked compartment shown in a forward guiding position; Fig. 12 is a vertical longitudinal view showing the 30 positions of the guiding means and severing means at the beginning of the feeding stroke; Fig. 13 is a similar view of the same parts at the 35 end of the feeding stroke and just after the severing operation; and Fig. 14 is a vertical trans-
verse sectional view of the writing table and means for holding the transferring material such as carbon coated paper.

Referring to the drawings showing one em-
bodyment of the invention, 15 designates a casing 40 which also serves as a frame for enclosing and supporting the operating mechanisms. The casing may be made of any suitable material and in any suitable form but, as shown, is of elongated rectangular form. The bottom and sides of the casing are in one piece and the ends of the sides which are slightly longer than the bottom are turned inwardly to form flanges 16 partially closing the two ends of the casing (Fig. 2). In the rear end of the casing is mounted a removable drawer 17 without sides adapted for holding a supply of paper folded zigzag and known as a flatpack and the outer exposed side 18 (Fig. 2) of this drawer overlaps and engages the side flanges 16 on said rear end to prevent the drawer being pushed too far into that end of the casing. A knob 19 facilitates manipulation of the drawer. Mounted in the forward end of the casing is a drawer 20, the front 21 of which overlaps the side flanges 16 on that end and closes it. This drawer is intended to receive the auditor's copies and the upper part of its rear end is separated from the sides, extended and turned rearwardly to form a slide 22 (Fig. 4) for the cutoff auditor's 55 copies to pass into the drawer. The rear top portion of the casing is closed by a flanged cover 24 having hinges 23 pivotally mounted on screws 27 in the frame so that the cover may be freely raised when necessary (Fig. 3). The downward-
60 turned flange at the rear of the cover laps over the upper edge of the drawer 17 to hold it within the casing. The cover 24 is provided with a rectangular opening 28 to expose that portion of the paper available for writing. The 65 70 75

forward end of the casing is also provided with a flanged cover 30 having an end flange adapted to overlap the upper edge of the front panel of the drawer 20 to hold it in the casing and any suitable means may be provided for locking this cover in place to prevent tampering with the auditor's copy.

5 Mounted in the rear part of the casing just below the cover 24 is a writing table or support 32 (Fig. 4), the rear end of which is turned tightly around a rod 33 having reduced ends mounted loosely in the sides of the casing. The forward end of the writing table or support rests loosely upon a transverse reenforcing bar 35, reversed 10 U-shaped in cross section, the two ends of which are fastened to the two sides of the casing by screws 36. The writing table and rod 33 are pivotally movable so that it may be raised when required to give access to the interior of the rear 15 part of the casing. The sides of the writing table may be turned downwardly to form flanges 37 for stiffening the table to prevent bending when being written upon. In order to guide the paper as it is drawn upwardly around the rear end of 20 the writing table by the feeding movement, a pair of disks 38 may be mounted on the rod 33 in 25 adjusted position.

For feeding the paper forward after each writing 30 operation, a pair of gripping mechanisms is provided, one on each side for gripping a forward corner of the paper and suitable means is provided for imparting a reciprocating movement to the gripping mechanisms and for operating them to grip and release the paper at the 35 appropriate times.

Each of the gripping mechanisms comprises a lower fixed jaw 40 and a movable upper jaw 41 both of elongated plate form horizontally positioned (Figs. 5-7). The jaw 40 is formed integral with a vertical plate 42 having its two ends 43 and 44 turned at right angles outwardly, between which is a fixed sleeve 46 adapted to slide 40 on a rod 47, supported at its rear end in the cross U-bar 35 and at its forward end in a vertical transverse bar 48 fastened by its laterally turned ends to the sides of the casing by screws 49. The upper jaw 41 has a vertical body portion 55 which is pivotally mounted on a screw stud 56 mounted in the fixed jaw plate 42 between that plate and the sleeve. The two gripping 45 mechanisms are connected together to move in unison by a tie bar 57 fastened to the ends 50 44 by screws 58.

The gripper mechanisms are reciprocated on 55 their supporting rods 47 by means of a pair of rack-bars 60, the rear ends of which are supported by a pair of housings 62 in the rear part of the casing. Each of these housings is provided with a longitudinal flange 63 whereby it is fastened to the inner face of one side of the casing by screws 64 (Fig. 3). These housings are of sufficient length to permit full movement of the rack-bars without separation therefrom. The forward end of each rack-bar is connected to one 60 of said gripping mechanisms, which supports that end, by the following means. A split block 66 having a bottom recess for receiving the rack-bar is adjustably fastened thereto by a pair of screws 67 and this block is pivotally connected by a pin 68 to a cam 69 pivotally mounted on a screw stud 70 held by a nut 71 in the vertical plate 42 of the lower jaw of the gripping mechanism. This cam is provided with two cam edges 72 and 73 adapted 75 one or the other to engage a tail part 74 of the movable jaw. The cam edges are in substantial

right angled relation to each other and are over the center sufficiently to require an appreciable force to operate from one position to the other, a spring 75 interposed between the tail part and the end 44 tending to keep jaws open. 5

To impart a feeding movement to the gripping mechanisms the rack-bars are longitudinally reciprocated by any suitable means and one form of such means is shown comprising gears operated from a cam shaft adapted to be rotated either by a crank or by power, such as a motor. The rack-bars 60 are faced downwardly and meshing with each rack-bar is a large gear 80, these two gears being fixed to a transverse shaft 81, the two ends of which extend into longitudinal slots 15 82 in the side walls of the casing (Fig. 4). Each large gear 80 carries riveted to its outer face a smaller gear 84 meshing with a short rack-bar 85 faced upwardly and fastened to the side wall of the casing by screws 86. The rack-bars 60 are 20 moved horizontally by moving the shaft 81 longitudinally of the casing, thereby rolling the smaller gear on the short rack-bar 85 by means of a pair of cranks 86 each connected at one end to the shaft 81 and at the other end to a crank disk 25 87 by a pin 88. The two crank disks 87 are fixed to a cam shaft 90 adapted to be rotated either by a crank or by power. This shaft is rotatably supported in the ends of two rearwardly extending brackets 91 having their feet 92 secured by 30 screws 93 to a plate 94 or partition extending across the casing approximately midway its ends.

This partition is secured in position by right-angled brackets 96 fastened to the plate by screws 97 and to the sides of the casing by rivets 98. 35 This partition also serves to reinforce the sides of the casing to prevent inward or outward movement of the same.

The revolution of the shaft 90 and cam disks through the instrumentality of the two cranks 40 86 moves the shaft 81 longitudinally of the casing in the slots 82 thereby causing the small gears to travel by rotation on the short rack-bars and to turn the large gear during said travel to reciprocate the rack-bars longitudinally. By 45 means of this construction, I secure a relatively long throw of the rack-bars with a relatively small diameter crank thereby enabling me to use a very compact mechanism for operating the rack-bars and one which takes up very little 50 space.

For rotating the cam shaft 90 and cam disks 87, I provide a gear 100 (Fig. 9) riveted to the inner face of one of the crank disks on one side of the casing which meshes with a gear 101 55 mounted on a stud shaft 102 extending outwardly through one side of the casing, the outer end of which may be provided with a crank (not shown) or connected to a motor 103 (Fig. 1) by any suitable means. In case a crank is used, the gear 60 101 is preferably made of the same diameter as the gear 100 but when a motor is employed, it is preferable to reduce the diameter of the gear 101 to suit the power of the motor. The gear 101 is held on the stud shaft by a nut 104. 65

For severing the used portions of paper, any suitable severing means may be employed and one such is shown comprising the following. A fixed shearing member 105 is fastened in oblique position to a cross bar 106 having squared ends 70 whereby it is secured by screws 107 to the U-bar 35. Between the squared ends, the cross bar is bevelled and screws 108 are used for fastening the blade 105 to the bevelled top surface of the bar with one edge projecting over the bar in position 75

to be engaged by a knife blade 110 mounted transversely of the casing for vertical reciprocation and having an oblique cutting edge 111 to produce a shearing action.

- 5 The movable knife blade 110 is supported on a frame made up of a cross bar 112 and two uprights 113, which frame is guided by means of milled blocks 114 fastened by screws 115 to the central partition 94. A pair of springs 117 under tension at all times are each connected at one end to screws 118 set in the partition 94 and at the other end to the cross bar 112. These springs normally tend to hold the movable knife blade raised. To hold the knife blade in a depressed position ready for upward movement when released at the appropriate time, a pair of dogs 120 is provided, said dogs being fixed, one on each end of a shaft 121 rotatably mounted in the lower end of two depending arms 122, each 20 formed on one of said brackets 91. The free end of each dog enters a cut out recess on one end of the cross bar 112 engaging a shoulder formed thereby. The movement of these two dogs is controlled by a cam 124 fixed on shaft 90 upon 25 the periphery of which cam rides a roll 125 carried in the end of an arm 126 fastened to the shaft 121. The tension of the springs 117 by exerting upward pressure on the dogs 120 holds the cam roll 125 in engagement with the periphery of the cam 124 at all times. This cam is provided with a depressed portion so that when 30 the roll 125 reaches this part of the cam in the revolution of the shaft 90, it permits the arm 126 to move inwardly toward the shaft 90 raising the dogs and permitting the springs 117 to pull the 35 knife frame and the knife upwardly. The cam surface 128 which permits this movement is abrupt so that the upward movement of the movable knife blade at this point is rapid in 40 order to effect the shearing action. The cam surface 130, however, has a more gradual incline so that the knife is drawn downwardly into an inoperative position by a more gradual movement of the dogs.
- 45 In order to separate the lowermost used copy from the other copies to deliver it into the auditor's drawer, a rearwardly extending deflector plate 135 is provided having a forward turned down edge 136 fastened by screws 137 to the cross 50 bar 48 in the forward end of the machine. This is an elongated plate having its rear corners cut off on the bias and the rear end of this deflector plate extends into close proximity to the central partition 94. Normally, the rear end of the deflector plate is slightly depressed as shown in 55 Fig. 4. On each side near its forward end the plate is cut out to form a forwardly facing tongue 140 having an upturned end, which tongue is bent downwardly to lie normally somewhat below 60 the main body portion of the plate. Fastened to the top of the tie bar 57 connecting the two gripping mechanisms is an angle bar 142 which is adapted to engage the bottom face of the central portion of the deflector plate but not the 65 tongues on the rearward movement of the gripping mechanisms in order to raise the plate and to contribute to the operation of separating the bottom sheet from the other sheets on the forward feeding movement and delivering it into 70 the auditor's compartment or drawer 20.

In order to insure this separation and delivery, it is necessary to bridge the space between the forward ends of the cut paper sheets and the rearward end of the deflector plate (Fig. 12) and 75 for this purpose, a yoke plate 145 (Fig. 11) is

adapted to be thrown forward just prior to the feeding movement in order to guide the bottom copy under the rear end of the deflector plate. The yoke plate is of thin metal having its ends provided each with a slot to permit it to be mounted on the ends of two upright arms 150 fastened to the two ends of a shaft 151 rotatably mounted in the brackets 91 (Fig. 2). The arm 150 on one end of the shaft is extended downwardly to form an arm 152 in the end of which is mounted a cam roll 153 adapted to engage the periphery of a cam 154 fixed on the shaft 90, this cam being so shaped that at the appropriate time a spring 155, attached to one of the arms 150 at one end and to the central partition 94 at the other end is permitted to pull that arm in a forward direction thereby rocking the shaft 151 and moving the yoke plate forwardly and over the rear end of the deflector plate into the position as shown in Fig. 12, the forward end of the yoke plate being bent upwardly to lap over the rear end of the deflector plate so that the bottom copy will not strike against the rear edge of said latter plate when fed forward.

These mechanisms are so timed that the yoke plate is thrown forward just before the feeding starts and is retained in a forward position until the forward end of the bottom sheet has passed an appreciable distance beyond the front or forward edge of the yoke plate and is on its way into the compartment.

In Fig. 4 is shown diagrammatically a flatpack 160 arranged in the drawer 17 with the end of the paper 161 turned around the rear end of the writing table and broken off adjacent said rear end in order to illustrate the manner in which the paper is drawn out of the supply drawer by the forward feeding movement. For the sake of clearness the flatpack is shown as composed of but a single strip or web of paper 40 but it may be assumed that this single line may represent two or more webs because in machines of this description it is generally customary to use at least three webs.

In Fig. 2 the register is shown with a web of 45 paper 161 inserted therein, the used sheets 162 having been fed forward and severed just before they are kicked back by the rearward movement of the gripping mechanisms. In this view the web is shown as provided with the usual printed 50 forms thereon and with filing holes 163 and lines of perforation 164 which permit the forms to be folded zigzag in the form of a flatpack.

In the operation of the register hereinbefore described, a supply of paper in the form of a 55 flatpack, so-called, is placed in the drawer 17. The flatpack is made up of a plurality of strips or webs of paper in superposed relation, perforated transversely and folded in zigzag fashion on said 60 perforated lines as illustrated in Fig. 4. The paper comprising the two or more superposed strips or webs of paper is led upwardly around the rear end of the support or writing table with the ends of the webs in register with each other and in alignment with the cutting edge of the fixed knife. 65

In adjusting the paper in the register the carbon sheets are interleaved with the webs and secured in position transversely of the webs as shown in Fig. 15. The register is then ready for operation and the operator writes upon the exposed surface of the top sheet the record of sale or other data which is reproduced by the carbon sheets on the underneath webs.

When the entry has been completed the register is then operated either by crank or by starting 75

the motor. Normally, the gripping mechanisms when the machine is at rest are located a short distance rearwardly the front end of the register, the jaws being open, and upon starting the machine the rack-bars are moved longitudinally in a rearward direction to move the gripping mechanisms in the same direction. When the gripping mechanisms engage the central partition 94 they stop with the forward corner edges of the paper between the open jaws, but the rack-bar continues its movement for a short distance thereby turning the cam 69 from the position shown in Fig. 7 to the position shown in Fig. 6 which closes the jaws of each gripping mechanism to grip the forward corner edges of the paper webs. The upper jaw in these mechanisms is of spring metal so as to exert an appreciable pressure on the paper to hold all the webs together against relative movement.

On the rearward movement of the gripping mechanisms the deflector plate is raised into the position shown in Fig. 12 by the angle iron 142 (Fig. 4) and before the feeding starts the yoke 145 is thrown forward to guide the bottom copy, which is under the yoke, beneath the deflector plate. Upon the completion of the movement of the rack-bar rearwardly, it then starts on a forward movement and the paper webs are fed forwardly by the gripping mechanisms until those mechanisms engage stops 170 in the form of screws threaded through the end bar 48 and held by nuts 171 in adjusted position. At this point the rack-bar still continues its movement and operates the cam 69 from the position shown in Fig. 6 to the position shown in Fig. 7 and thereby opens the jaws to release the paper.

During the feeding movement the bottom copy is carried along underneath the deflector plate but as soon as the gripping jaws open the depressed tongues 140 of the deflector plate (Fig. 4) forces the forward end of that copy out of the jaws and that end drops down into the drawer 20 in the auditor's compartment and the severing of all the used copies which occurs at the end of the feeding movement releases the rear end of the bottom copy which the deflector plate forces downwardly. As a result of this action, the bottom copy slides into the compartment in smooth unruffled condition and there is no possibility of the compartment being clogged up to stop the operation of the register.

At the completion of the severing, the rear ends of all of the severed sheets except the bottom sheet lie on the top edge of the movable knife 110 (Fig. 13) and the knife remains in this position for a short interval until the gripping mechanisms move rearwardly a short distance to their normal position. This is accomplished by providing a short dwell in the knife cam 124. This rearward movement of the gripping mechanisms kicks the severed copies in a rearward direction over the fixed knife blade 105 into a position to be grasped by the operator. The register is then ready for the next operation.

It will be observed that in the register of my invention, the movement of the paper webs is controlled absolutely at all times so that there is no possibility of the webs getting out of alignment with each other. The severing of the used copies eliminates all crumpling of the auditor's copies since they accumulate and build up in a flat condition in a pile in the locked compartment and in numerical order. This saves considerable time and labor because, heretofore, in registers in which the auditor's copy has been fed into the

compartment in continuous form with the expectation that it would naturally fold in zigzag form into a flatpack, an expectation which, however, was frequently not realized, it has been necessary after removing a day's work from the compartment to separate the leaves at the perforations for filing purposes. When a business is of sufficient size to warrant the use of a number of registers with a large number of sales or orders each day, the work of separating them in the auditor's department is a large item of expense.

It is to be understood that my invention is not to be limited to the particular form of register herein shown and described since it is capable of embodiment in various other forms of construction, all within the purview of the following claims.

What I claim is:—

1. A device of the character described comprising, in combination, a casing provided with a writing support and a compartment forward said support, a deflector plate in said compartment extending rearwardly toward said support, means for feeding a plurality of superposed webs forwardly from said support and means including a movable plate for bridging the space between said support and said deflector plate to direct the bottom web into said compartment.

2. A device of the character described comprising, in combination, a casing provided with a writing support and a compartment forward said support, a deflector plate in said compartment extending rearwardly toward said support, means for feeding a plurality of superposed webs forwardly from said support, a plate interposed between said webs and means for moving said plate forward to bridge the space between said support and said deflector plate to direct the bottom web into said compartment on said feeding movement.

3. A device of the character described comprising a casing provided with a writing support and a compartment forward said support and adapted to be locked, a deflector plate in said compartment extending rearwardly toward said support, means for feeding a plurality of superposed webs forwardly from said support, a plate interposed between said webs, means for moving said plate forwardly to bridge the space between said support and said deflector plate to direct the bottom web into said compartment on the beginning of said feeding movement and to withdraw said plate before said feeding movement is completed, and means for severing said webs after each feeding movement.

4. A device of the character described comprising, in combination, a casing provided with a writing support and a compartment forward of said support, a deflector plate in said compartment extending rearwardly toward said support, means for feeding a plurality of superposed webs forwardly over said support a predetermined distance, said feeding means comprising means for gripping the forward ends of said webs and means for reciprocating said gripping means, said reciprocating means having a longer stroke than said gripping means in order to open and close said gripping means after the reciprocation thereof has ceased, and means including a movable plate for bridging the space between said support and said deflector plate to direct the bottom web into said compartment.

5. A device of the character described comprising, in combination, a casing provided with a writing support and a compartment forward of

said support, a deflector plate in said compartment extending rearwardly toward said support, means for feeding a plurality of superposed webs forwardly over said support a predetermined distance, said feeding means comprising a pair of jaws, means for opening or closing said jaws and means for reciprocating said jaws, said reciprocating means having a longer stroke than said jaws in order to open and close the same after the reciprocation thereof has ceased, and means including a movable plate for bridging the space between said support and said deflector plate to direct the bottom web into said compartment.

6. A device of the character described comprising, in combination, a casing provided with a writing support and a compartment forward of said support, a deflector plate in said compartment extending rearwardly toward said support, means for feeding a plurality of superposed webs forwardly over said support a predetermined distance, said feeding means comprising a pair of jaws for gripping the forward ends of said webs, means for opening and closing said jaws and means for reciprocating said jaws to fit said webs, said reciprocating means having a longer stroke than said jaws in order to open and close the same after reciprocation thereof has ceased, a plate adapted to be interposed between said webs and means for moving said plate forward to bridge the space between said support and said deflector plate to direct the bottom web into said compartment on each feeding movement.

7. A device of the character described comprising a casing provided with a writing support and a compartment forward of said support and adapted to be locked, a deflector plate in said compartment extending rearwardly toward said support, means for feeding a plurality of superposed webs forwardly over said support a predetermined distance, said feeding means comprising a pair of jaws for gripping the forward ends of said webs, means for opening and closing said jaws and means for reciprocating said jaws to feed said webs, said reciprocating means having a longer stroke than said jaws in order to open and close the same after reciprocation thereof has ceased, a plate adapted to be interposed between said webs, means for moving said plate forwardly to bridge the space between said support and said deflector plate to direct the bottom web into said compartment on the beginning of said feeding movement and to withdraw said plate before said feeding movement is completed, and means for severing said webs after each feeding movement.

8. A device of the character described having, in combination, a casing provided with a writing support and a compartment forward of said support, a deflector plate in said compartment extending rearwardly toward said support, means for feeding a plurality of superposed webs forwardly over said support a predetermined distance, said feeding means comprising a pair of jaws for gripping the forward ends of said webs, a cam member for opening or closing said jaws, said cam requiring a greater force for its operation than is required for reciprocating said jaws, a pair of fixed stops for limiting the movement of said jaws in both directions and means pivotally connected to said cam member for reciprocating said jaws between said stops to feed said webs, said reciprocating means having a longer stroke in both directions than said jaws in order to operate said cam for opening or closing said

jaws after reciprocating movement thereof has ceased, and means including a movable plate for bridging the space between said support and said deflector plate to direct the bottom web into said compartment.

9. A device of the character described comprising a casing provided with a writing support and a compartment forward of said support and adapted to be locked, a deflector plate in said compartment extending rearwardly toward said support, means for feeding a plurality of superposed webs forwardly over said support a predetermined distance, said feeding means comprising a pair of jaws for gripping the forward ends of said webs, a cam member for opening or closing said jaws, said cam requiring a greater force for its operation than is required for reciprocating said jaws, a pair of fixed stops for limiting the movement of said jaws in both directions and means pivotally connected to said cam member for reciprocating said jaws between said stops to feed said webs, said reciprocating means having a longer stroke in both directions than said jaws in order to operate said cam for opening or closing said jaws after reciprocating movement thereof has ceased, a plate interposed between said webs, means for moving said plate forwardly to bridge the space between said support and said deflector plate to direct the bottom web into said compartment on the beginning of said feeding movement and to withdraw said plate before said feeding movement is completed, and means for severing said webs after each feeding movement.

10. A device of the character described comprising, in combination, a casing provided with a writing support and a compartment forward of said support, a deflector plate in said compartment extending rearwardly toward said support, means for feeding a plurality of superposed webs forwardly from said support, means including a movable plate for bridging the space between said support and said deflector plate at the beginning of the feeding movement to direct the bottom web into said compartment, and means for severing said webs after each feeding movement; said feeding means being adapted for ejecting rearwardly the severed portions of all said webs except for the bottom web.

11. A device of the character described comprising, in combination, a casing provided with a writing support and a compartment forward of said support, a deflector plate in said compartment extending rearwardly toward said support, means for feeding a plurality of superposed webs forwardly from said support, means for directing the bottom web under said deflector plate, means for severing all of said webs after each feeding movement and means for ejecting rearwardly the severed portions of all said webs except the bottom web.

12. A device of the character described comprising, in combination, a casing provided with a writing support and a compartment forward of said support, a deflector plate in said compartment extending rearwardly toward said support, means for feeding a plurality of superposed webs forwardly from said support, means including a movable plate for bridging the space between said support and said deflector plate at the beginning of the feeding movement to direct the bottom web into said compartment, means for severing all of said webs after each feeding movement and means for ejecting rearwardly the

severed portions of all said webs except the bottom web.

13. A device of the character described comprising, in combination, a casing provided with a writing support and a compartment forward said support, means for feeding a plurality of superposed webs forwardly from said support, means for directing the bottom web into said compartment, means for severing all of said webs after each feeding movement and means for ejecting rearwardly the severed portions of all said webs except the bottom web.

14. A device of the character described comprising, in combination, a casing provided with a writing support and a compartment forward said support, deflecting means in said compartment extending rearwardly toward said support, means for feeding a plurality of superposed webs forwardly from said support, movable means for bridging the space between said support and said deflecting means at the beginning of the feeding movement to direct the bottom web into said compartment, means for severing all of said webs after each feeding movement and means for ejecting rearwardly the severed portions of all said webs except the bottom web.

15. A device of the character described comprising, in combination, a casing provided with a writing support and a compartment forward said support, a deflector plate in said compartment extending rearwardly toward said support, means for feeding a plurality of superposed webs forwardly from said support, a plate interposed between said webs, means for moving said plate forward to bridge the space between said support and said deflector plate at the beginning of the feeding movement to direct the bottom web into said compartment and means for severing all of said webs after each feeding movement.

16. A device of the character described comprising, in combination, a casing provided with a writing support and a compartment forward said support, a deflector plate in said compartment extending rearwardly toward said support, means for feeding a plurality of superposed webs forwardly from said support, a plate interposed between said webs, means for moving said plate forward to bridge the space between said support and said deflector plate at the beginning of the feeding movement to direct the bottom web into said compartment, means for severing all of said webs after each feeding movement and means for ejecting rearwardly the severed portions of all said webs except the bottom web.

17. A device of the character described comprising, in combination, a casing provided with a writing support and a compartment forward said support, a deflector plate in said compartment extending rearwardly toward said support, means for feeding a plurality of superposed webs a predetermined distance forwardly from said support, a plate interposed between said webs and means for moving said plate forward to bridge the space between said support and said deflector plate to direct the bottom web into said compartment on said feeding movement.

18. A device of the character described comprising, in combination, a casing provided with a writing support and a compartment forward said support, means for feeding a plurality of superposed webs forwardly from said support, means for directing the bottom web into said compartment on said feeding movement, means for severing all of said webs after each feeding

movement and means for ejecting rearwardly the severed portions of all of said webs except the bottom web.

19. A device of the character described comprising a frame, a writing support and means for feeding a continuous web of paper over said support, said means comprising a rack bar mounted for longitudinal movement, a shorter rack bar fixedly mounted below said movable rack bar, a gear rotatably mounted in said frame and meshing with said movable rack bar and carrying a gear of smaller diameter fixed thereto and in mesh with said short rack bar, a pair of jaws for gripping the forward end of said web, said jaws being mounted for reciprocation in a path parallel to said movable rack bar, a pair of stops for limiting the reciprocation of said jaws in both directions, a cam for opening and closing said jaws, said cam being pivotally connected to said movable rack bar and means for rotat- 20 ing said larger gear for reciprocating said movable rack bar to feed said web forwardly over said writing support, said rack bar having a longer movement than said jaws in order to close or open said jaws to grip or release the said web 25 after the reciprocation of said jaws in one direction or the other has ceased.

20. A device of the character described comprising a frame, a writing support, a rack bar mounted for longitudinal movement, a shorter 30 rack bar fixedly mounted below said movable rack bar, a gear rotatably mounted on said frame and meshing with said movable rack bar and carrying a gear of smaller diameter fixed thereto and in mesh with said short rack bar, means for 35 gripping the forward ends of a plurality of webs laid over said writing table, said means being mounted for reciprocation in a path parallel to said movable rack bar, a pair of stops for limiting the reciprocation of said gripping means in both 40 directions, a cam for opening and closing said gripping means, said cam being pivotally connected to said movable rack bar and means for reciprocating said movable rack bar to feed said webs forwardly over said writing support, said 45 rack bar having a longer movement than said gripping means in order to close or open said gripping means to grip or release the said webs after reciprocation of said means in one direction or the other has ceased and means for 50 severing said webs after each feeding movement.

21. A device of the character described comprising a casing having a compartment adapted to be locked, a writing support, means for feeding a plurality of continuous webs of paper over 55 said support, said means comprising a rack bar mounted for longitudinal movement, a shorter rack bar fixedly mounted below said movable rack bar, a gear meshing with said movable rack bar and carrying a gear of smaller diameter fixed 60 thereto and in mesh with said short rack bar, means for gripping the forward ends of said webs, said means being mounted for reciprocation in a path parallel to said movable rack bar, a pair 65 of stops for limiting the reciprocation of said gripping means in both directions, a cam for closing and opening said gripping means, said cam being pivotally connected to said movable rack bar and means for reciprocating said mov- 70 able rack bar to feed said webs forwardly over said writing support, said rack bar having a longer movement than said gripping means in order to close or open said means to grip or re- 75 lease the said web after movement of said jaws

in one direction or the other has ceased, means for guiding the bottom web into said compartment and means for severing said webs after each feeding operation.

- 5 22. A device of the character described comprising a casing having a compartment adapted to be locked, a writing support, means for feeding a plurality of continuous webs of paper over said support, said means comprising a rack bar 10 mounted for longitudinal movement, a shorter rack bar fixedly mounted below said movable rack bar, a gear meshing with said movable rack bar and carrying a gear of smaller diameter fixed thereto and in mesh with said short rack bar, 15 means for gripping the forward ends of said webs, said means being mounted for reciprocation in a path parallel to said movable rack bar, a pair

of stops for limiting the reciprocation of said gripping means in both directions, a cam for closing and opening said gripping means, said cam being pivotally connected to said movable rack bar and means for reciprocating said movable rack bar to feed said webs forwardly over said writing support, said rack bar having a longer movement than said gripping means in order to close or open said means to grip or release the said web after movement of said jaws in one direction or the other has ceased, means for guiding the bottom web into said compartment, means for severing said webs after each feeding operation and means for ejecting rearwardly the severed portions of all said webs except the bottom web. 10 15
